WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

COMBINED FILLING FORK AND WEFT-REPLENISHING MECHANISM

Application filed March 12, 1928. Serial No. 261,148.

This invention relates to improvements in automatic weft replenishing looms and it is the general object of the invention to combine the means for actuating the filling stop motion with a portion of the weft replenishing mechanism.

Looms as ordinarily constructed are provided with a filling stop motion which operates to arrest the loom when there is a fault in the filling. These motions are ordinarily of two types, namely, center stop motions which have a fork to operate in a well located approximately at the center of the lay, and the side stop motions which have a tilt-able fork which cooperates with the filling and a vertical grid on the lay at one side of the cloth. In either type of motion the detection for filling comes during the forward motion of the lay, the detection ordinarily being somewhat later in the side stop motions than in the center stop motions. With side stop motions it is customary to have a regularly moving actuator move forwardly when the lay is in its extreme forward position and if weft is present the fork will be tilted by engagement with the weft so that a forwardly extending tail or hook will be out of the path of the actuator. This actuator is usually driven by a cam on the bottom shaft and receives a motion every second pick of the loom.

Multicolor weft replenishing mechanisms as employed commercially include in their construction a vertically reciprocable block or rod on the upper end of which is mounted a floating lever. When the shuttle is on the plain or magazine end of the loom the detector is in engagement with the filling when the lay is in its foremost position and it is at this time that the rod receives a downward motion. The floating lever carried by the rod will clear a controller pin if sufficient yarn is present, but if, as the lay reaches its foremost position, the weft detector gives an indication of weft depletion the controller pin will lie under the lever to interrupt the downward movement of the latter and thereby initiate replenishment.

It will be seen that the actuator for the side stop motion and the block or rod for the

floating lever of the replenishing mechanism have movements at substantially the same time and it is an important object of my invention to derive the movements for the filling fork actuator and the floating lever rod from the same source.

In multicolor weft replenishing mechanisms where a side filling fork is used it is necessary that the fork be on the magazine side of the loom. This is due to the fact that on the opposite end of the loom where the shifting shuttle boxes are located there will always be one or more idle shuttles, the filling of which would operate to rock the tilting fork of a side stop motion on every forward beat of the loom should the filling fork be located on that side of the loom, that is, the box side. As a matter of practical construction, therefore, it is necessary to have the side stop motion located on the magazine side of the loom and as previously pointed out the motions for the side stop motion and the floating lever come at practically the same time in the cycle of the pick of the loom and may therefore be derived conveniently without lengthy connections from the same driving member.

With these and other objects in view which will appear as the description proceeds, my invention resides in the combination and arrangement of parts hereinafter described and set forth in the claims.

In the accompanying drawings, wherein I have shown a convenient embodiment of my invention,

Fig. 1 is a side elevation of a loom having my invention applied thereto, parts being in section,

Fig. 2 is an enlarged front elevation taken in the direction of arrow 2, Fig. 1, showing parts of the magazine not shown in Fig. 1,

Fig. 3 is a side elevation taken in the direction of arrow 3, Fig. 2,

Fig. 4 is a top plan view, parts being in section, taken in the direction of arrow 4, Fig. 2, and

Fig. 5 is a detailed vertical section on line 5-5 of Fig. 2.

Referring to the drawings, the loom frame 10 has a shipper handle 11 the upper end

of which is movable in a slot 12 cast in bracket 13 secured to the loom frame. The shipper handle is normally held in the notch 14 when the loom is running and is located behind the finger 15 of a lever 16 pivoted on stud 17 extending vertically from and secured to the bracket 13. As shown in Figs. 3 and 4 the left hand end of the lever 16 is received in a pocket 18 formed in the forward end of a slide 19 guided in a plate 20 secured to the frame 10.

A filling fork 21 is pivoted as at 22 to the rear end of the slide 19 and has a forwardly extending tail 23 which is slotted as at 24 in Fig. 4 and said fork also has substantially vertical tines 25 which cooperate with a grid 26 secured to the lay L. An actuator head 27 is normally located in the opening 24 and moves forwardly on alternate beats of the loom when the lay is in its front position.

When weft W is present it will engage the tines 25 to rock the fork 21 to the position shown in Fig. 1, thus lifting the slotted portion 24 out of the path of the head 27 and the latter will move forwardly in a slot 28 formed in the slide 19. When weft is absent, however, the tines 25 are not moved forwardly and the head, as the same moves forwardly, engages the tail 23 to move the slide 19 forwardly. This movement on the part of the slide causes a rocking of lever 16 in a counter-clockwise direction as viewed in Fig. 4 around stud 17 and causes finger 15 to move the shipper handle 11 out of the notch 14. The shipper handle will then move to loom stopping position.

The matter thus far described in connection with the filling stop motion is of common construction and operates in the usual manner, the only difference being that the head 27 as shown herein is somewhat different in form but performs the same functions as the head in the ordinary stop motions.

Weft replenishing mechanisms of the multicolor type such as shown in prior patent to Ryon No. 1,030,748 include a magazine frame 30, see Fig. 2, in which is mounted for vertical reciprocation one or more slides 31 having upper and lower lugs 32 and 33, respectively, which cooperate with a finger 34 of the so-called color slide C. Said slide moves in a direction transverse to the slides 31 and is supported in bearings 35 extending from the plate 30. A color slide has a tongue 36 which has sliding engagement with a lever 37 pivoted on a shaft 38 which forms part of the color slide. Said lever 37 is pivotally connected as at 39 to the upper end of rod or link 40 the lower end of which is adjustably connected to the left hand end of an actuator or floating lever 41. Said lever floats about a pivot defined by stud 42 carried at the upper end of a reciprocating block 43 the lower end of which is adjustably connected to the pump rod 44 which, as shown in Fig. 1, is pivotally connected as at 45 to the forward end of a cam lever 46. The latter lever is pivoted to a fixed stud 47 and has the rear end 48 thereof extended into a cam groove 49 formed on a cam 50 which is keyed or otherwise secured to the bottom shaft 51.

As shown in Figs. 2 and 4 the right hand end of the floating actuator lever 41 extends into an upstanding horn 52 formed as part of a stand 53 which may be secured in any manner to the loom frame. Said horn is provided with a slot 54 into which the actuator lever projects and said horn is provided at the upper end thereof with a pin 55 which extends across the slot 54. Below the floating lever is located a controller pin 56 which is positioned by the weft detecting mechanism not shown.

During the normal running of the loom the bottom shaft 51 will be given a complete rotation every second pick of the loom and the cam 50 will be so designed and placed on the bottom shaft as to move the block 43 downwardly when the shuttle is on the magazine side of the loom and the lay is at front center or in its extreme forward position. If under these conditions the controller 56 be out of the path of the actuator lever the latter will descend without interruption to assume the dotted line position shown in Fig. 2. Should the pin 56, however, be under the actuator lever said pin will become the fulcrum of the actuator lever as the block 43 descends and the left hand end of said lever together with the rod 40 as viewed in Fig. 2 will move downwardly. The effect of this will be to raise finger 34 so that the slide 31 corresponding to the active shuttle will be raised. It is to be understood that there are several slides 31, one for each active shuttle or each shuttle box on the opposite end of the loom. This operation, as previously stated, takes place when the shuttle is on the magazine side of the loom.

When the shuttle has been picked across to the opposite side of the loom the block 43 will receive an upward movement to cause the actuator lever to assume the position shown in dot and dash lines in Fig. 2, the pin 55 becoming the fulcrum around which the lever moves. This latter operation occurs on alternate beats of the loom when the shuttle is either on the box end or is being picked toward the box end and away from the magazine which is independent of the action of the weft detector. The matter described heretofore as being controlled by the cam 50 is substantially the same as that shown in patent to Ryon No. 1,030,748 and forms no part of my present invention.

My present improvements relate to means for actuating the filling stop motion from the same moving member which is an essential part of the weft replenishing mechanism, and in carrying my invention into effect I

extend an arm 60 rearwardly from the plate or stand 20 and secure in the same an upwardly extending stud 61. Pivotally mounted on said stud is a lever 62 the left hand arm of which as shown in Fig. 4 carries the head 27. The right hand arm 63 has an upwardly extending portion 64 provided with a pair of slots 65 through which extend bolts 66. Said bolts or screws extend into a cam member 67 the vertical position of which may be adjusted because of the slots 65. Said cam member 67 has at the upper portion thereof a substantially vertical surface 68 which at the lower end thereof merges with an inclined surface 69 as shown in Fig. 5.

The rearwardly extending end of the stud 42 is enlarged as at 70, as shown in Fig. 4, and may be rounded for cooperation with the cam member 67. The upwardly extending face 68 is sufficiently high to have contact with the portion 70 of the stud when the block 43 is in its highest position so that if desired the lever may be held against the stud as a stop by means of torsion spring 71. Said spring surrounds stud 61 and as shown in Fig. 4 has one end in engagement with the arm 60 and the other end in engagement with the lever, tending to move the latter in a right hand direction around stud 61 as viewed in said Fig. 4.

Under normal conditions the cam 50 will cause the block 43 and stud 42 to descend as already described when the shuttle is on the magazine side of the loom and the lay is substantially in its extreme forward position. At this time the controller pin 56 will have received its movement from the detector and the actuator lever 41 may descend. As the block 43 moves downwardly the end 70 will ride along inclined face 69 to rock the lever 62 in a counter-clockwise direction as viewed in Fig. 4 around stud 61, the effect of which is to move the head 27 forwardly. If weft is present behind the fork 21 the latter will be rocked to the position shown in Fig. 1 and said head 27 may continue its forward movement without contact with the tail 23, but should the weft be absent said head will engage the tail to move slide 19 forwardly and operate to stop the loom, as previously described.

From an inspection of Fig. 4 it will be apparent that the block 43 is capable of causing the actuator lever to cooperate with the controller pin 56 independently of any relation which may be brought about by said block 43 between the head 27 and the hook 23. The controller pin 56 and the tail 23 may cooperate with their respective regularly moving actuators on the same beat of the loom and each will act independently of the other. It has been customary heretofore to employ a long lever and a cam on the bottom shaft in addition to that indicated at 50 in Fig. 1 for operating the side stop motion, but by the mecha-

nism set forth herein the latter motion can be caused to operate by making use of that part of the motion of the block 43 which comes at the proper time in the cycle of the operation of the loom to cause correct functioning of the filling fork and slide 19.

From the foregoing it will be seen that I have provided a very simple means for actuating a weft replenishing mechanism and a filling stop motion from the same cam by making use of that portion of the cam which operates during the time in which the detection for weft presence by the filling fork may be made. It will also be noted that the relative locations of the plunger 43 and slide 19 as they occur ordinarily in a loom make it convenient to pivot lever 62 between these devices. While I have shown a particular form of lever and means for communicating motion from the block 43 to the head 27 yet I do not wish to be limited to this showing. Furthermore, it will be seen that those portions of the replenishing mechanism which are controlled by the detector not shown may act independently of the filling stop motion, although each of these devices derives its operating movement from the same source. By proper location of the cam member 67 the head 27 may be caused to move forwardly at the proper time.

Having thus described my invention it will be apparent that changes and modifications may be made therein by those skilled in the art without departing from the spirit and scope of the invention and I do not wish to be limited to the details herein disclosed, but what I claim is:

1. In a weft replenishing loom having a lay, weft replenishing mechanism including as a part thereof a rocking color slide element which receives a motion on detecting beats of the loom when exhaustion of weft is indicated when the lay is substantially in its foremost position, a filling stop motion, and a single moving member to cooperate with the element to give the latter a rocking movement on weft exhaustion indicating beats of the loom and also the filling stop motion to effect operation of the filling stop motion.

2. In a weft replenishing loom having a lay, a weft replenishing mechanism including as a part thereof a rocking color slide member having a movement on detecting beats of the loom when exhaustion of weft is indicated when the lay is in its extreme forward position, a movable element formed as part of the replenishing mechanism to be operatively related to the member to rock the same to initiate replenishment, and a filling stop motion to be operatively related upon absence of weft to the member to cause stopping of the loom.

3. In a loom having a lay, a weft replenishing mechanism having a color slide, a filling stop motion, a single regularly moving member having a movement when the lay

- is in its forward position on detecting beats of the loom, and means to transfer movement of said member either to the color slide of the replenishing mechanism or to the filling stop motion to effect either initiation of replenishment or stoppage of the loom through the stop motion.
4. In a loom having a lay, a weft replenishing mechanism having a color slide, a filling stop motion effective to stop the loom on absence of weft, and a regularly moving actuator operatively connected to the color slide to have a movement when the lay is in its forward position on weft exhaustion indicating beats of the loom to move the color slide and common to the replenishing mechanism and filling fork to actuate either or both of said devices.
5. In a loom having a lay, a weft replenishing mechanism having a color slide located at one side of the loom, a filling stop motion located at the same side of the loom and effective to stop the loom upon absence of weft, and a member receiving a regular movement when the lay is in its forward position on detecting beats of the loom when the shuttle is on the replenishing mechanism side of the loom, and means to operatively connect said member either to the color slide of the replenishing mechanism or the filling stop motion, whereby said member is effective either to initiate replenishment or to stop the loom.
6. In a loom having a lay, a weft replenishing mechanism having a color slide located at one side of the loom, a filling stop motion located at the same side of the loom and effective to stop the loom upon absence of weft, and a member receiving a regular movement when the lay is in its forward position on detecting beats of the loom when the shuttle is on the replenishing mechanism side of the loom, and means to operatively connect said member either to the color slide of the replenishing mechanism or the filling stop motion, whereby said member is effective either to initiate replenishment or to stop the loom, said member being located between the weft replenishing mechanism and the filling stop motion.
50. In testimony whereof I have hereunto affixed my signature.

WALTER H. WAKEFIELD.
